UNITED STATES PATENT OFFICE

105,793

DESIGN FOR A SHOE

Nishon Gardner, Lynn, Mass., assignor to C. A. Grosvenor Shoe Co., Worcester, Mass., a corporation of Massachusetts

Application January 19, 1937, Serial No. 67,148

Term of patent 3½ years

To all whom it may concern:

Be it known that I, Nishon Gardner, a citizen of the United States of America, residing at Lynn, in the county of Essex and State of Massachusetts, have invented a new, original, and ornamental Design for a Shoe, of which the following is a specification, reference being had to the accompanying drawing, forming part thereof.

In the drawing,

Fig. 1 is a perspective view looking toward the right side of a shoe embodying my design; and
Fig. 2 is a side view slightly in perspective of the opposite side of the shoe.

I claim:

The ornamental design for a shoe, substantially as shown.

NISHON GARDNER.
